METHOD AND APPARATUS FOR MIXING

Morris M. Bean, Yellow Springs, Ohio, assignor to Morris Bean and Company, Yellow Springs, Ohio, a corporation of Ohio

Original application December 2, 1953, Serial No. 395,737. Divided and this application May 28, 1957, Serial No. 666,500

2 Claims. (Cl. 18—47.5)

This invention relates to apparatus for thoroughly mixing dry and liquid materials to form a soft, smooth mix, and for delivering the resulting mix through a convenient conduit. More particularly, the invention relates to the separation and injection of slurries of settable materials such as plaster of Paris and the like.

In the preparation of such mixtures, difficulty has been experienced in so blending dry and wet constituents as to insure a smooth, uniform mixture free from air bubbles. Another difficulty is to reach such smooth uniform consistency before the binder has set up and thereafter to expel the mix from the apparatus before it has set. Where this problem has been met by using a slow setting mix to give time for the mixing operation plus necessary holding in transit before it is molded, production has been unduly delayed with serious increase in the capital tied up in mold equipment ("mold" is used broadly herein to include patterns, etc. as well as external molds).

The present invention aims to provide improved apparatus for effecting a thorough mixing of dry and wet constituents into a slurry and holding the slurry ready for molding during the variable delays normally encountered in manufacturing and yet to supply the mix on demand in condition for prompt setting up in a mold.

An important feature of the invention is the simple mixing device which not only effects the mixing of the dry and wet constituents of the slurry, but also subjects the solid particles of the slurry to a rubbing and squeezing operation. This results both in improving the uniformity of the mixture and at the same time in driving out any gases.

Another important feature of the invention is the novel ejection means and its arrangement in the apparatus.

It is important also that all parts which contact the mix are so simple and accessible that an effective washing of all operating parts can be effected by a simple flushing operation.

Further important features are the maintenance of a controlled head on the slurry and automatic supply of materials to replace mix withdrawn from the machine. A novel construction of the ejector, particularly of the ejector piston, and the use of the ejector piston as a valve, are also important features.

Another important feature is that the cycling of the ejector pump and the inflow of materials are independent of time and flow but responsive to withdrawal of the mix. Especially important is that uniform ejection pressure is effective at all times except momentarily during retraction of the ejector piston.

Other objects, important features and advantages of the invention which have not specifically been pointed out hereinabove will appear when the following description and claims are considered in connection with the accompanying drawings, in which:

Figure 1 is a side elevation of mixing and ejecting apparatus embodying the present invention, certain

2

appurtenant parts being shown diagrammatically, certain parts in phantom and part of the heat exchanger being broken away:

Figure 2 is a view, on enlarged scale, mainly in vertical section but partly in elevation, of the mixing chamber and mixing mechanism together with the ejection pump connected therewith;

Figure 3 is a similarly enlarged sectional detail showing the ejector piston at the lower end of its stroke and with its expansible gland contacting the cylinder wall to prevent by-passing of the slurry around the piston;

Figure 4 is a sectional view of a modification in which a fixed ring gear engages pinions on the several roller shafts to positively determine the rotation speed of the mixing rollers;

Figure 5 is a fragmentary cross-sectional view similar to Figure 3 showing a modified expansible piston.

In the embodiment of the invention herein illustrated, a suitable frame 8 is provided for supporting the operating parts of the mechanism. Advantageously, this is a conventional type with an upright pillar mounted on a base provided with casters for full mobility. In the drawings as here shown, this frame 8 is partially broken away for clear showing of the operating parts.

The device embodying my invention comprises a mixing chamber 2, in which the constituents of a slurry to be formed are mixed, and mixing means 10 operating in said mixing chamber to crush and rub the constituents of the slurry against the chamber wall. In this embodiment, mixing chamber 2 is shown as a casting carried by a bracket 6 of the frame 8. The mixing chamber is funnel-shaped with the bottom part 11 of its walls at a greater angle to its axis than along their major depth.

The rollers 10 are mounted in bearings in a yoke 12 which has a hub 14 rotated in bearing 16 supported on bracket 20. This is also attached to the vertical frame member 8. The belt 22 drives the hub 14 from pulley 24 on a gear reducer 26 driven by a motor 28.

As shown, the bearings for each of the rollers 10 are eccentrically mounted in a cylinder 36 fitted in the yoke 12. These cylinders can be rotated by a tool inserted in one of a plurality of holes 38 and thus the rollers 10 can be adjusted radially to bring them into the desired tangential contact with the inner surface of the mixing chamber 2. Each cylinder 36 can be locked in its adjusted position by means of a set screw 40.

The bracket 20 as shown has an open center 42 through which extends conduits for the materials to be mixed. Proportioned feed of these materials is supplied, the dry materials through the tube 44 and the liquid through the spray ring 46 and pipe 48. The proportioning of these materials is advantageously effected automatically by apparatus such as that disclosed in my said Patent No. 2,574,238. However, in order to avoid repeating here the extensive description and drawings of the proportioning apparatus as given in my patent, I have shown diagrammatically, in Figure 1, an ordinary proportioning feeder 49 which measures out the powder feed in response to or in conjunction with flow of the

liquid, the liquid, in turn or conjointly, being controlled by a relay and solenoid valve, from the feeler circuit including probe 52. As the level of the slurry in chamber 2 rises to that shown at 50, electric probe 52 completes a circuit to actuate a solenoid valve controlling the flow of liquid; and, with the flow of liquid stopped, no further dry material can be fed by the proportioning device until the liquid flow is re-established.

If the proportioning feed of Patent No. 2,574,238 is used, the apparatus of Figure 1, except for 49 is used with the apparatus of the patent above the wet-core unit 27. The chute 59 of the patent then becomes chute 44 of the apparatus herein set forth and the water supply pipes

72 of the patent and distributor 74 become pipe 48 and distributor 46 above described. The feeding and proportioning apparatus of Figures 1-7, 9-12 and 21, as well as the mounting and delivery means of Figures 22-29, can be used substantially as shown in said patent. This combination then would operate as follows:

As the level of the slurry in chamber 2 rises to that shown at 50, electric probe 52 energizes a relay which in turn energizes the timer, which shuts off a motor for a definite time interval allowing the slurry level 50 to drop a short distance, depending upon the rate of discharge from nozzle 161. This motor drives the plaster meter wheel and the water meter pump geared together to maintain a uniform consistency, and at the expiration of the time interval the motor turns on and the liquid level approaches the electric probe 52.

This mixing chamber as above described makes possible the satisfactory operation at maximum demand, thus requiring very little storage of the mixed material, which would have to be wasted when the production was interrupted for more than a few minutes.

The cylindrical rollers 10 travelling over the conical surface lag behind said surface at the top and turn faster than a rolling speed at the bottom. Thus, a rubbing and smearing action highly effective for mixing the powder into the liquid is achieved. The drag forward on the top of each roller is balanced against the drag back on the bottom of the roller. Only a section near the center of the roller actually rolls on the conical surface of the chamber without slippage. The conical ends of the rollers extending to and even over the outlet from the mixing chamber and rotating at relatively high speed, create a final turbulence in the exit and assure that all material before leaving the mixing chamber will have been rubbed between the rollers and the chamber wall.

The discharge end of the mixing chamber 2 merges into a cylinder 54 provided with an ejector piston 70. The cylinder 54 is secured by a clamping ring 59 bolted over flange 56 and onto the bottom of the chamber 2.

A coupling 66 shown, also in Figure 2, connects the cylinder 54 to the discharge line, including pipes 68, 148 and 160. The inside of this coupling is smooth for streamline flow and is contoured similar to the bottom 78 of piston 70 (see Figure 3).

The probe 69 extending down from piston 70 aids in keeping pipe 68 open.

The piston 70 comprises essentially a gland, here shown as a ring 71 of rubber-like material, advantageously a thick-walled tube of "pure gum" vulcanized rubber or any elastomer composition sufficiently hard and strong and tough to resist the high fluid pressures encountered and the repeated extrusion and retraction from, and between flange 74 and nut 78. In the modified piston shown in Figure 3, a toroidal ring 71a like an automobile tire is used, with its inner rims clamped respectively to the flange 74a and the nut 78a. In either case, when the gland is squeezed, it extrudes laterally into the shape shown in Figure 3. When the flange 74 and nut 78 are moved apart, the gland is extended longitudinally and retracted radially to the shape shown in Figure 2, in which the slurry may by-pass the piston. As shown in greater detail in Figure 3, lateral extrusion and retraction of the piston are effected by the relative movement of the hollow rod 72 and the center rod 76.

Instead of mechanically expanding the piston ring 71, as shown in Figures 2 and 3, this function can be performed pneumatically or hydraulically, e. g., by using for ring 71b an inflatable annular tube as shown in Figure 5 with an opening at 79 connecting it through the bore of tubular rod 72b, to the hose 140b. The ring 71b is cemented to the rim of flange member 74b, particularly around the hole 79.

Great care must be exercised in design of piston 70 to keep from introducing air between 70 and 71, or to prevent leaks around tube 71a or 71b.

Rod 72 is also flanged at its upper end and rigidly connected to the bottom of the cylinder 82, and rod 76 is connected to piston 80 in the cylinder 82, so that fluid pressure in the cylinder compresses and extrudes ring 71. A spring 84 in this cylinder urges piston 80 and rod 76 downward relative to rod 72, to retract ring 71 to the form shown in Figure 2.

The cylinder 82 is moved bodily by the piston rod 86 driven by piston 88 in cylinder 90 mounted on bracket 92 of frame 8. Rod 86 is threaded for adjustment and provided with lock nuts, to control the amount of squeeze on piston ring 71 so as to assure a tight fit in cylinder 54 without excessive friction.

A three way solenoid valve 98 operates to introduce air pressure into the cylinder 82 to extrude ring 71 when its solenoid is energized and to vent air from the cylinder to retract the gland when the solenoid is released.

A four-way solenoid valve 102 introduces air pressure above piston 88 and vents the space below the piston when its solenoid is energized, thus urging piston 70 down into cylinder 54 and imposing a suitable head on the slurry for delivery from the apparatus; when the solenoid is released, valve 102 vents the top and introduces pressure below the piston 88 to lift piston 70. A limit switch 106, normally closed and having one contact positioned to be engaged by finger 108 on cylinder 82, limits the injection stroke of the piston 70 by breaking the energizing circuit of valve 102.

A controlling switch 116 as shown may be put into any of three positions: "run," "off," and "start." When it is in the "start" or the "run" position, it energizes the motor 28, e. g. by conventional circuit connections (not shown).

In the "start" position this switch makes connections around the relay 123, i. e., the circuit of valve 98 is closed independently of the timer 112; whereas in the "run" position, the switch connects both solenoid valves 102 and 98 through contacts 126 and 128 of relay 123 thus making them subject to control by the timer. If this switch 116 were left in the "start" position, the piston 70 would not be effectively retracted, but would serve only as a stopper. If the switch 116 were left always in the "run" position, it would not operate valve 98 until relay 123 had received a pulse from the timer; and then pumping would start. The "start" position of switch 116 provides for operation of fluid motor 80-82 to stopper chamber 2 before the timer 112 is started.

An electronic (or other available) pulse timer 112, operated from the feed line 110 through the wires 114 and 118 and the hand operated switch 122, closes the circuit to the relays 123 for short "pulses" at time intervals predetermined by the setting of the timer. Contacts 126 and 128 are provided on relay 123 to be closed by its armature; and the connections 130, 132 and the normally closed limit switch 106 provide a holding circuit for the winding of the relay so that, once closed, it remains closed through this holding circuit until switch 106 is opened. Once opened, the relay remains open until a pulse from the timer 112 re-energizes it.

Contact 126 closes the above mentioned holding circuit for relay 123 and the contact 128 closes circuits to the solenoid valves 98 and 102. At first, the energizing circuit for relay 123 is through the connection 124, timer 112, contacts 122; but when relay 123 is operated the circuit is through connection 130, limit switch 106 and connection 132.

Air-flow control valves are provided at 134 and 136 to regulate the speed of piston 88 and ejector piston 70 connected to it. An air control valve 138 similarly regulates the speed at which the ejector piston 70 is expanded or contracted by movement of piston 80. Air line 140 is a flexible hose or pipe to accommodate vertical movement of the cylinder 82.

In Figure 4 of the drawings is shown a modification of the embodiment shown in Figures 1 to 3 wherein the

rollers 10a are positively rotated by bevel gears 141 which mesh with the fixed ring gear 142 mounted on bracket 20a so that the rotation of the yoke 12 drives the pinion 141 over the ring gear 142 and thus rotates each of the rollers 10a. The ring may be external or internal. By the proportioning selected for the respective diameters of the pinion gears 141 and the ring gear 142, any desired speed of rotation may be given to the rollers 10a and any desired rubbing action attained.

In the operation of this mechanism, switch 116 is moved to its "start" position, whereupon the motor 28 is started and solenoid valve 98 is energized to cause the expansion of the injector piston 70. This closes the outlet from the mixing chamber 2.

The liquid and dry materials to be mixed are then introduced by the automatic proportioning device 49 and through the conduit 44 and a spray head 46 respectively. The cylindrical rollers 10 meanwhile have been started in rotation by motor 28, driving through belts 22. The rollers operate against the inner surface of the mixing chamber 2 with both a rolling action to squeeze out any air bubbles, a crushing action to break up any lumps of the powder, and a rubbing action against the inner surface of the chamber to thoroughly wet the surface of every particle and produce uniform slurry. By reason of the fact that the upper ends of the roller 10 travel around the longer circumference of the top of the funnel-shaped chamber 2 while their lower ends traverse a shorter path at the bottom of the chamber, the rubbing action varies both in direction and degree. The frustoconical end 144 of the rollers 10 and the fitting conical bottom 11 of the chamber permits the rolling, rubbing and crushing action to extend substantially to the outlet of the chamber 2 and thus prevents settling out of solids and retards solidification of the slurry when the discharge is shut off.

The introduction of liquid and dry constituents and the mixing continue until the material fills the chamber 2 to the level 50, when it contacts the electrical probe 52 to stop further introduction of the constituents.

When the chamber 2 is thus filled, the switch 116 is moved from "start" position to "run" position and the switch 122 is closed to start the timer 112. Removing the switch 116 to the "run" position releases the solenoid valve 98 permitting exhaust from the cylinder 82 to allow the piston 80 to return and retract the gland 71. As timer 112 moves, it soon sends a pulse to the relay 123. After each pulse, the relay 123 is held energized by the holding circuit through contacts 126, connections 130, 132 and limit switch 106 until limit switch 106 is opened. With contacts 128 closed, both valves 98 and 102 are operated so that piston 80 is moved up, expanding piston 70 to a tight fit in cylinder 54, and piston 88 is driven down causing piston 70 to move down and eject the slurry from cylinder 54 through the line 68, 148 and 160.

At the end of this stroke, a projection 108 on cylinder 82 strikes and opens limit switch 106, which drops relay 123; and solenoids 98 and 102 are thus de-energized which reverses both solenoid valves to retract the piston gland 71 and lift the piston 70.

The liquid supplied through the pipe 48 and spray head 46 is advantageously cold enough to substantially retard the setting of the slurry. In the case of plaster of Paris, I thus use water at a temperature about 0° to 20° C. To the same end, the chamber 10 and/or cylinder 54 may be jacketed or provided with a cooling coil and a refrigerant fluid circulated to chill the mix to that range. It is desirable, however, that the slurry set rapidly when it has been introduced into the mold. In the illustrative embodiment of the invention, therefore, a heater 146 is provided so that the slurry is delivered from the discharged nozzle into the mold in a condition ready for quick setting, advantageously 50-65° C. The required temperature is automatically maintained by sup-

plying to a steam jacket 146 saturated steam at a pressure corresponding to a slightly higher temperature, e. g., of a pressure about 2 to 30 p. s. i. above atmospheric. The condensate drains from the low point of this jacket 5 through a pipe 152 and a thermostatic trap 154 and the discharge pipe 156. A steam gauge 158 shows the pressure and/or temperature. A shut-off valve 150 provides for stopping the heat or reducing the rate of heating, if the discharge is to be cut off for any substantial time or 10 unduly retarded.

A flexible tube 160 provided with a nozzle 161 receives the slurry from the tube 148 and enables the operator to deliver it at the desired points in the molds, etc.

The slurry is delivered from the nozzle 161 at a tem-

15 perature near that of its maximum setting speed and in a stream of about $\frac{1}{4}$ to $\frac{1}{2}$ " diameter or larger, (the particular nozzle being chosen to give the most advantageous size stream for filling the plaster into the detail of the particular mold). The velocity of the stream, 20 which is regulated by the air pressure supplied through the valve 102, is adapted to drive the plaster into the detail by its momentum but without "whipping it up" so as to entrain any air. Thus, in one preferred embodiment the air supplied by the piston 80 keeps a head of 25 100 lbs. per square inch on the slurry.

As one example: A dry mix containing 42% gypsum cement, 47% fine sand, 8% talc and 3% terra alba was mixed with water at 5° C. to the consistency of soft mud or slurry. This could be held safely in the machine for 30 four minutes and it would take about 15 minutes thereafter to set. The chamber 2 was, therefore, designed to hold only enough of the mix for about a two-minute supply for normal use. After this mix had been pumped through the heater 146, its temperature was raised to 50° 35 C. and the mix was then set in 2.8 minutes, thus allowing adequate time for filling it into the mold and for it to flow and form itself into the detail of the mold.

As above pointed out, one of the great advantages of 40 this invention is that slurries such as gypsum plaster can be made and a supply kept at a temperature so low that setting will not occur in the machine and yet will occur promptly after delivery. Because the piston and the mixing device are immersed in the slurry throughout the operation of the apparatus and operate through the open 45 upper surface of the material in the hopper without glands or other devices which could leak air below the surface of the slurry, the danger of introducing air bubbles is substantially entirely eliminated and the mechanical design of the apparatus is greatly simplified by the avoidance 50 of the need for stuffing boxes or glands to control such air leakage into the apparatus.

When use of the apparatus is to be discontinued, the feed is cut off and pumping continued until the hopper is substantially emptied.

55 Water for flushing out the apparatus is run in at 166. This serves to wash out the mixing hopper 2 and to clean the rollers 10 and piston 70 and all parts with which the slurry has been in contact. By leaving the apparatus running while the flushing water is running in and through 60 the apparatus, pump 70 and rollers 10 serve to agitate the water and to give it relatively high velocity along the surfaces which need to be washed and thus facilitate the cleaning of all parts which have been covered by the plaster. Rod 69 also helps in assuring a thorough washing 65 of the pipe 68.

I claim:

1. The process of preparing a settable and moldable slurry including a water-setting constituent, such as gypsum plaster, which consists in mixing the theretofore 70 dry constituents of the slurry with water, chilling the slurry to a temperature sufficiently below atmospheric to strongly retard the setting of the slurry, rubbing and squeezing the wetter solid particles of the slurry during the mixing until occluded gases have been substantially 75 completely expelled while retaining the temperature of

the slurry substantially below atmospheric, then ejecting the slurry under pressure into a form with heating of the slurry as it is discharged.

2. The process as defined in claim 19 wherein the amount of slurry being mixed at any time is substantially less than that consumed at the current rate of use within the setting time of the slurry at said low temperature, the mixing is substantially continuous and additional con-

stituents are added as mixed slurry is discharged and in amounts corresponding to those discharged as slurry.
